UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

SPECIFICATION forming part of Design No. 12,112, dated January 11, 1881.

Application filed December 6, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration, forming a part of this specification.

The design is composed of, first, a groundwork of small squares or blocks placed in parallel rows extending both longitudinally and transversely of the carpet, each block having a spot of contrasting color in its center; secondly, angular light centers A B C, inter-

rupting the groundwork and surrounded by dark borders or stripes; and, thirdly, sprays of leaves and flowers partially covering the light centers and groundwork.

I claim—

The design for a carpet, substantially as shown and described.

In testimony whereof I have signed my name to this specification, in the presence of two subscribing witnesses, this 3d day of December, 1880.

THOMAS J. STEARNS.
